W. J. KRAMER

TRAFFIC SIGNAL FOR AUTOMOBILES AND THE LIKE

Filed May 9, 1921

INVENTOR
William J. Kramer

BY Ralph Waldo

ATTORNEY

UNITED STATES PATENT OFFICE.

WILLIAM J. KRAMER, OF ST. LOUIS, MISSOURI, ASSIGNOR OF ONE-HALF TO IRA W. HENDRICKS, OF ST. LOUIS, MISSOURI.

TRAFFIC SIGNAL FOR AUTOMOBILES AND THE LIKE.

Application filed May 9, 1921. Serial No. 467,862.

To all whom it may concern:

Be it known that I, WILLIAM J. KRAMER, a citizen of the United States, residing at the city of St. Louis, State of Missouri, have invented a certain new and useful Improvement in Traffic Signals for Automobiles and the like, of which the following is a specification, reference being had to the accompanying drawing, forming a part thereof.

10 This invention relates to a certain new and useful improvement in traffic signals for automobiles and the like, the chief object of my present invention being to provide a simple, compact and inexpensive attachment which may be readily mounted upon the car and which comprises a swingable arm that may be conveniently selectively actuated to indicate or signal the occupants of following cars or traffic that the automobile or car equipped with my new signalling device or attachment is about to stop or slacken speed or to turn to the right or to the left, as the case may be.

With the above and other objects in view, 25 my present invention resides in the novel features of form, construction, arrangement, and combination of parts hereinafter described and afterwards pointed out in the claims.

30 In the accompanying drawing,

Figure 1 is a fragmental plan view in outline of an automobile equipped with a signalling attachment embodying my invention;

35 Figure 2 is an enlarged plan view of the signalling attachment or device with the signalling-arm in "stop" or "slacken speed" position as in Figure 1;

40 Figure 3 is a side view of the attachment, partly in section on the line 3—3 Figure 2, with the signalling-arm in normal or "straight-ahead" position;

45 Figure 4 is a reduced detail elevational view of the signalling-arm, showing the same in full lines in normal or "straight-ahead" position and in dotted lines in its various selective traffic signaling positions; and

50 Figure 5 is a reduced detail elevational view of one of the contact or switch-members of the attachment.

Referring now more in detail to the said drawing, which illustrates a practical embodiment of my invention and in which like

reference characters refer to like parts throughout the several views, 1 indicates a preferably tubular member or short pipe-bar which, in use or operation, is rigidly located in a horizontally disposed position upon a car A preferably to the front of the instrument-board B and with one end projecting somewhat outwardly to the side of the car, as best seen in Figure 1. It will be understood that the member or bar 1 may be of any suitable length to meet the requirements of any particular car, the bar preferably extending at its inner end to a point adjacent the steering-post C.

55 Mounted upon the tube or bar 1 adjacent its inner end and preferably locked in position upon the tube 1 by a set-screw or other suitable means 2, is an approximately U-shaped block or bearing-member 3; and threaded or otherwise fastened upon the other or outer end of tube 1 is a barrel or 60 cylindrical bearing 4 apertured for communication with the interior of pipe 1.

65 Mounted at its inner end portion for rotary movement in the legs of the block 3, is a shaft 5 suitably elongated, as shown, 70 to project rearwardly of the car through an insulation block 6 suitably fixed upon the instrument-board B, the outer or rear end of the shaft 5 being provided with an actuating wheel or other handle 7 located 75 preferably within convenient reach of the driver of the car. Fixed upon the shaft 5 and located for rotary movement intermediate the legs of the block 3, is a gear 8.

80 Projecting through and disposed for rotary movement in the bearing 4, is a suitable preferably tubular shaft 9 slotted longitudinally to provide communication between its interior and the interior of pipe 1. Fixed upon the rearward end of shaft 9, 85 in operative alignment with the gear 8, is a second gear 10 having driven connection with the first gear 8 by means of a chain or other suitable flexible member 11; and held in position upon an extension 10' of pinion or gear 10 by a cap or the like 12, for purposes shortly appearing, is a mirror-disk or other reflecting member 13.

90 Fixed upon the forward end of shaft 9, is a nut or the like 14, fixed in which at its lower end is a suitably elongated arm preferably in the form of a tube 15, the tube 15, nut 14, and shaft 9 being suitably aper-

tured to provide communication between the interior of shaft 9 and tube 15. Mounted upon the outer or free end of arm 15, is a lamp-socket 16 for an electric lamp-bulb or the like 17, and also mounted for removal upon the free outer end of arm 15 to enclose the lamp 17, is a globe 18 composed of celluloid or other suitable preferably non-breakable translucent material.

10 Preferably embedded in the insulation block 6, are arcuated contact-members 19—19, one of which is adapted for electrical connection through a wire 23 with one side of the lamp socket 16, and the other of which is suitably grounded upon the car by means of a wire 22, and leading from the other side of the lamp socket 16 to a storage battery or other source of current 21 carried by the car is a conducting wire 20.

15 20 Fixed upon and for movement with the shaft 5 for bridging and thereby electrically connecting the contact members 19—19, is a switch-arm 24.

Normally the arm 15 is in the upright straight-ahead position thereof illustrated in Figure 3 and in full lines in Figure 4 and engages a movement limiting-stop 25 provided upon the bearing-member 4, and when the arm 15 is in such normal position, the switch-arm 24 is in the position thereof illustrated in dotted lines in Figure 5, the circuit to the lamp 17 being open. Should now the driver desire to signal following cars or traffic that he is about to turn to the right, 35 or to stop or slacken speed, or to turn to the left, as the case may be, the wheel 7 is grasped and turned to the left, whereby, through the chain-connected gears 8 and 10, the arm 15 is selectively actuated or shifted accordingly, 40 as indicated by dotted lines in Figure 4, a spring or other yielding member 26 fastened upon the member 4 and provided with a series of spaced depressions 27 engaging the arm to releasably hold the same in its 45 normal, as well as in its several shifted signaling positions. A second stop 28 also fixed upon the member 4 and suitably spaced from stop 25 serves to limit the movement of the arm 15 to its final shifted signaling position. It will be obvious that, when the arm 15 is so shifted, the switch-arm 24 will engage the contacts 19—19 and thereby close the circuit to the lamp 17 for illuminating the globe 18, as in night-time or darkness, 55 the mirror 13, by reflection and in co-operation with illuminated globe 18, enabling following traffic in darkness to observe the particular shifted signaling position of the arm 15.

60 On reversely actuating or turning the wheel 7, both the signaling arm 15, its carried lamp 17 and globe 18, and the switch-arm 24 will be returned to normal straight-ahead position.

65 Enclosing the gears 8 and 10 and their con-

nnecting chain 11, is a protective shell or casing 29.

My new signaling attachment is simple and inexpensive in form and construction, 70 may be readily mounted upon the automobile, and has been found exceedingly convenient and efficient in performing its intended functions.

I am aware that changes in the form, construction, arrangement, and combination of 75 the several parts of the attachment may be made and substituted for those herein shown and described without departing from the nature and principle of my invention.

Having thus described my invention, what 80 I claim and desire to secure by Letters Patent is:

1. An automobile-signaling attachment comprising, in combination, a supporting-bar adapted for rigid location horizontally 85 upon the automobile forwardly of the instrument-board thereof, spaced bearings fixed on the bar, shafts mounted for rotation in said bearings at right angles to the bar, a shiftable signaling-arm fixed at an end upon one 90 of the shafts and disposed at a right angle thereto, gears fixed upon both the shafts, a flexible member connecting the gears, and an operating-member fixed upon the other shaft for manually actuating the gears to shift 95 the arm through rotary actuation of said one shaft.

2. An automobile-signaling attachment comprising, in combination, a supporting-bar adapted for rigid location horizontally 100 upon the automobile forwardly of the instrument-board thereof, spaced bearings fixed on the bar, shafts mounted for rotation in said bearings at right angles to the bar, a shiftable signaling-arm fixed at an end upon one 105 of the shafts and disposed at right angles thereto, gears fixed upon both the shafts, a flexible member connecting the gears, an operating member fixed upon the other shaft for manually actuating the gears to shift the arm through rotary actuation of said one shaft, and spaced stops fixed on one of the 110 bearings for engagement with said arm for limiting the shiftable movement thereof.

3. An automobile-signaling attachment 115 comprising, in combination, a supporting-bar adapted for rigid location horizontally upon the automobile forwardly of the instrument-board thereof, spaced bearings fixed on the bar, shafts mounted for rotation in said bearings at right angles to the bar, a shiftable signaling-arm fixed at an end upon one of the shafts and disposed at a right angle thereto, gears fixed upon both the shafts, a flexible member connecting the gears, an operating member fixed upon the other shaft for manually actuating the gears to shift 120 the arm through rotary actuation of said one shaft, and a yielding-member fixed upon one of the bearings and provided with 125

130

a series of spaced depressions for engagement with the arm for releasably locking the same in shifted signaling positions.

4. An automobile-signaling attachment comprising, in combination, a supporting-bar adapted for rigid location horizontally upon the automobile forwardly of the instrument-board thereof, spaced bearings fixed on the bar, shafts mounted for rotation in said bearings at right angles to the bar, a shiftable signalling-arm fixed at an end upon one of the shafts, and disposed at right angles thereto, gears fixed upon both the shafts, a flexible member connecting the gears, an operating member fixed upon the

other shaft for manually actuating the gears to shift the arm, through rotary actuation of said one shaft, a pair of spaced stops fixed on one of the bearings for engagement with the arm for limiting the shiftable movement thereof, and a spring member fixed upon said one bearing intermediate and stops and provided with a series of depressions for engagement with said arm for releasably locking the same in shifted signaling positions.

In testimony whereof, I have signed my name to this specification.

WILLIAM J. KRAMER.
